UNITED STATES PATENT OFFICE.

BENJAMIN THOMAS SELMAN, OF CHATTANOOGA, TENNESSEE.

DESIGN FOR A CHARM.

SPECIFICATION forming part of Design No. 28,627, dated May 17, 1898.

Application filed January 26, 1898. Serial No. 668,075. Term of patent 7 years.

To all whom it may concern:

Be it known that I, BENJAMIN THOMAS SELMAN, a citizen of the United States, residing at Chattanooga, in the county of Hamilton 5 and State of Tennessee, have invented and produced a new and original Design for a Charm; and I do hereby declare the following to be a full, clear, and exact description of the same, reference being had to the accompanying drawings, forming a part thereof.

Figure 1 is a front view of a watch-charm or the like, showing my new design. Fig. 2 is a rear view of the same.

The material feature of the design is a heart-shaped plate A, surmounted by a bar B, having a short arm b, and a longer arm b' at right angles to the short arm. The bar is graduated to represent a carpenter's square. The right angle or corner b² is uppermost, the 15 arms being tangent to the upper curved edges of the plate A.

On the front of the plate A are delineated figures a of women, while the plain surface a' of the back affords space for an inscription of any kind. 25

It is evident that the design is applicable to lockets and similar articles as well as to charms.

Having thus described my invention, what I claim, and desire to secure by Letters Patent, is— 30

The design for a charm, as herein shown and described.

In testimony whereof I affix my signature in presence of two witnesses.

BENJAMIN THOMAS SELMAN.

Witnesses:
